UNITED STATES PATENT OFFICE.

WILLIAM H. McCUNE, OF VANDERGRIFT, PENNSYLVANIA.

SELF-CLEANING STILL.

1,010,508.

Specification of Letters Patent.

Patented Dec. 5, 1911.

Application filed February 14, 1911. Serial No. 608,546.

To all whom it may concern:

Be it known that I, WILLIAM H. McCUNE, of Vandergrift, in the county of Westmoreland and State of Pennsylvania, have invented a new and useful Self-Cleaning Still, of which the following is a full, clear, and exact description, reference being had to the accompanying drawings, forming part of this specification.

10 My invention relates to apparatus used in distilling water and more particularly relates to the construction and arrangement of means whereby the still is mechanically cleaned at frequent intervals without substantial interruption of the distilling operation or attention of the operator.

In the operation of such distilling apparatus heretofore the impurities in the water being distilled become concentrated and collect in the bottom portion of the retort of the still, the solids in the heated water becoming deposited and building up gradually on the inner surfaces of the still retort. The accumulation of such deposits is so rapid and the volume of the deposited matter so great that unless the retort is frequently cleaned the deposited matter on the inner surfaces of the still, which is an excellent non-conductor of heat, becomes so heavy as to seriously retard the effective operation and greatly reduce the distilling capacity of the apparatus. The usual method of cleaning such stills is, in the smaller stills, to remove the materials deposited in the retort by hand, and, in the larger sizes of such apparatus, to draw off the concentrated sludge and solid materials in the still through a valve-controlled opening in the bottom of the retort. In both of these methods the continuity of the distilling operation must be interrupted while the cleaning operations are being carried out, and considerable time is lost in again starting the apparatus in operation.

45 One object of my invention is to provide apparatus for distilling water having novel means whereby the still is automatically cleaned at regulated intervals and whereby the cleaning operations are performed mechanically without the assistance of an attendant and without substantial interruption in the continuous operation of the distilling apparatus.

Referring to the drawings, Figure 1 is a 55 sectional elevation showing distilling apparatus constructed and arranged in accord-

ance with my invention. Fig. 2 is a sectional plan on the irregular line II—II of Fig. 1, showing the relative arrangement of the retort, condensing worm or screw and the mechanism by which the retort of the still is automatically cleaned at pre-determined intervals.

In the drawings, 2 designates the retort of the distilling apparatus which as shown is 65 constructed of copper and has a cylindrical central portion connecting frusto-conical top and bottom portions. The smaller upper end of the frusto-conical top portion of the retort is provided with a cylindrical end 70 portion having a tightly fitting removable lid or cover 3. Leading from the upper portion of the retort 2 is a tubular worm or screw 4 formed of block tin and leading into the cooling chamber or tank 5 in which 75 cold water is constantly being supplied and the steam evolved in the retort 2 and passed through the worm is condensed, the so distilled water being delivered through the lower end of the worm 4 into a suitable receptacle such as a carboy. The inner surfaces of the retort 2 are usually tinned.

As shown in the drawings, a pipe coil 2' leads into and out of the bottom portion of the retort 2, steam being passed through this 85 pipe in order to heat and vaporize the water surrounding the coil in the retort. Also located in the lower portion of the retort is an annular gas burner 6 having a pipe 7 connected with a source of gas supply, the 90 burner 6 also being employed to heat and vaporize the water in the retort 2. Surrounding the upper portion of the retort is a cylindrical shell or hood 8 having a head 9 and being provided near its upper end with 95 small openings 10 through which the products of combustion from the gas burner 6 pass outwardly from the hood 8, this hood preferably, although not necessarily, being employed.

The retort 2 is connected to the cooling tank 5 in which the worm 4 is placed by means of a horizontal overflow pipe 11 and box 12 which is secured on and forms part of the cooling chamber 5. Within the box 105 12 is a vertically depending partition 13 having a small hole or series of holes 14 therethrough at a level slightly below the level 15 at which the water is maintained within the retort 2, and the level of the overflow outlet in the cooling tank. The hole or holes 14 are made of such size as to permit

water to flow from the cooling tank 5 at about the rate the water is vaporized in the retort 2 and the box 12 and pipe 11 and the holes 14 in the partition 13 are provided to 5 deliver a constant supply of water into the retort 2 to replace the water constantly passing therefrom in the form of vapor into the tubular worm 4 to be condensed therein.

The cooling chamber 5 is provided with 10 a water overflow pipe 16 and a water inlet pipe 17 (through which water is supplied to the cooling tank 5 and through the tank 5 to the retort 2) is connected into the lower portion of the condensing chamber 5.

15 A stop cock 18 is provided at a suitable location on the side of the cooling tank or condensing chamber 5 and beneath the stop cock 18 is a cylindrical tank 19 arranged to collect water running from the stop cock 20 18. The tank 19 is provided with a siphon 20 which is connected to the tank so as to make a water tight joint and which is of such size as to readily start to siphon the water in the tank 19 when supplied to this 25 tank at the rather slow rate at which the water is supplied from the drip cock 18. Braces 19^a are employed to secure the tanks 5 and 19 together in the relative position shown.

30 Beneath the tank 19 is a similar tank 21 of larger size, as shown, its capacity being about three times that of the tank 19. The tank 21 is arranged to collect the water discharged from the siphon 20, a siphon 22 being provided on the tank 21 which is arranged to discharge into the float tank 23 below the tank 21. The tank 23 is provided with a float 24 having feet on its bottom to hold the bottom of the float out of contact 40 with the bottom of the tank 23. A U-tube 25 forming a siphon is connected to the bottom of the float tank 23 so as to practically drain this tank when the siphon 25 is started in operation.

45 The lower, smaller end of the conical bottom on the retort 2 is provided with a drain pipe 26 and located at a suitable point in the length of this drain pipe is a stop cock 27 which is normally in closed position during 50 the operation of the apparatus. The stop cock 27 is provided with an operating lever arm 28 which is operatively connected to one end 29 of the bell crank formed by the levers 29 and 30. The bell crank is pivotally 55 connected to a support 31 which is secured to the drain pipe and the framework 32 supporting the apparatus. The outer end of the lever arm 30 of the bell crank is connected to the rod 33 on the top of the float 60 24 so as to open and close the stop cock 27 with the rising and falling of the float in the tank 23.

In the operation of my improved apparatus water is supplied through the pipe 17 65 and cooling chamber 5 to the box 12 and

through this box and the pipe 11 to the retort 2. Steam is then supplied to the steam heating coil 2' or else the annular gas burner 6 is lighted to heat the water in the retort 2, or in some cases both means of heating 70 may be employed. When the water becomes heated to the boiling point, the vapor which then arises passes upwardly in the retort and is led downwardly through the worm or condensing coil 4 and after the steam is condensed 75 the resulting distilled water is led outwardly through the condensing chamber 5 through the lower end of the condensing coil and is delivered into a carboy or other receptacle in readiness for use. 80

A supply of fresh water is constantly provided in the retort 2 through the pipe 11 and box 12 which connect the retort with the condensing chamber 5, and the condensing chamber or tank 5 is being constantly supplied with fresh water through the pipes 17, the water being constantly maintained 85 at the desired level in the apparatus by means of the overflow pipe 16.

The stop cock 18 is opened so as to drip 90 slowly into the tank 19, the rate of feed of water into this tank being regulated to suit the necessary requirements.

When the tank 19 becomes filled with water, the siphon 20 will be caused to operate and discharge the water in the tank 20 into the lower tank 21. The relative sizes of the tanks 19 and 21 are such that the lower larger tank has a capacity of about three times that of the upper tank 19, so that the 10 tank 19 will be emptied three times before the larger tank 21 is filled sufficiently to start the siphon 22 to operate and deliver the contents of this tank 21 into the float chamber 23. 105

The function of the siphon will be more readily understood by first assuming a construction in which the vessel 19 and siphon 20 are absent. In such case, where water is supplied drop by drop to the vessel 21, when the water reaches the level of the top of the lower curve of the bend in the siphon 22 it will simply flow over in a thin film, no siphonic action, properly speaking, taking place. But when the contents of the tank 19 are quickly supplied to the tank 21 and the tank 21 is sufficiently full, the siphon 22 is filled to the top of its bend and a true siphonic action takes place whereby the float 24 is quickly lifted to be as quickly allowed to sink, the chamber 23 being rapidly emptied by the relatively large siphon 25. 115 120

When the water in the tank 21 is delivered into the float tank 23, the float 24 is caused to rise in the tank 23 and through the bell crank connection formed by the rigidly connected levers 29 and 30 moves the lever 28 on the closed stop cock 27 from the horizontal position shown in Fig. 1 so as to extend vertically. When in this position the cock 125 130

27 is open and water in the bottom portion of the retort 2 will be drained from the retort. When this occurs the solid matter collected in the bottom of the retort will be 5 carried out of the retort by the water removed in this way.

When the float tank 23 has been filled with sufficient water the siphon formed by the U-pipe 25 will be started to operate and 10 the water drained from the float tank 23.

As the level of the water in the float tank is lowered the float 24 descends in this tank and, through the connecting bell crank mechanism closes the stop cock 27.

15 The frequency with which the retort 2 is drained is regulated by varying the volume of water discharged from the chamber into the siphon tank 19 by the drip cock 18 so that the number of times the retort 2 is 20 flushed in a given time can be readily changed.

When a quantity of water has been removed from the retort 2 by flushing the retort through the drain pipe 26 the water 25 again regains the desired level in the retort 2 in a short period of time, (ordinarily about two minutes with the apparatus illustrated), and the continuous operation of the apparatus is practically effected.

30 The advantages of my invention will be apparent to those skilled in the art.

By the provision of the novel means for automatically flushing the retort of the still at pre-determined intervals the collection of 35 objectionable solids in the bottom of the retort is overcome and prevented.

The novel arrangement of the flushing apparatus, as shown, permits of the flushing operations being carried out automatically without attention or manual labor, and the 40 still is maintained in an operative condition at all times.

Modifications in the construction and arrangement of the parts may be made.

The construction of the still and the construction of the flushing apparatus may be 45 changed and the relative location of the parts may be varied without departing from my invention as defined in the claims.

I claim:

1. A still comprising a retort having a valve-controlled outlet in the bottom thereof, mechanism for actuating said valve in opening and closing, and mechanical means for operating said valve actuating mechanism and regulating the time intervals at which said valve actuating mechanism is operated. 55

2. A still comprising a retort having a valve-controlled drain outlet in the bottom thereof, mechanism for actuating said valve in opening and closing, mechanical means for operating said valve actuating mechanism and means for varying the time intervals the valve is held in its closed position. 60 65

In testimony whereof, I have hereunto set my hand.

WILLIAM H. McCUNE.
